UNITED STATES PATENT OFFICE

WILLIAM M. BOENNING, OF MANITOWOC, WISCONSIN

FOLDING TABLE

Application filed January 13, 1932. Serial No. 586,367.

This invention relates to folding tables, and more particularly to light, portable card tables and the like.

The present invention is directed specifically to the hardware for pivotal attachment of the legs, and has for its object to provide an exceedingly simple, inexpensive, and at the same time rigid attachment, which is extremely easy to manipulate and securely retains the pivoted leg in extended or retracted positions.

Incidental to the foregoing, a more specific object of the invention resides in the provision of a channelled brace adapted to embrace the head of a stud carried by the leg to releasably lock the leg in open position and guide the same during retraction.

A further object resides in the provision of a novel bracket for pivotally connecting the leg to the table frame independently thereof, thus eliminating unsightly rivets and attaching devices on the outside of the table.

A still further object is to provide exceedingly simple means for tensional retention of the brace in both open and collapsed positions.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

Figure 1 is a fragmentary elevation of one corner of the table with the present invention applied thereto.

Figure 2 is a transverse detailed section taken on the line 2—2 of Figure 1.

Figure 3 is a similar view taken on the line 3—3 of Figure 1.

Figure 4 is a bottom plan section taken on the line 4—4 of Figure 1, and

Figure 5 is a vertical section taken on the line 5—5 of Figure 4.

Referring now more particularly to the accompanying drawing, the numeral 1 designates a table top of rectangular shape and provided with peripheral depending side strips 2 forming a frame for attachment of the legs, which nest within the frame when retracted. As best shown in Figures 4 and 5, the legs 3 are pivotally connected to the strips 2 by means of a bracket 4, which is formed from a single blank of material having laterally spaced ears 5 and 6, respectively.

Formed out of the back of the bracket is a tongue 7 which is secured to one of the side strips 2 by a screw 8, or other suitable attaching device. The ear 6 extends beyond the leg 3 and is provided with an offset portion 9 also secured to one of the side strips 2 by a screw 8, thus serving to slightly space the bracket 4 from the adjacent side strip.

As best shown in Figure 4, the leg 3 is pivotally connected between the ears 5 and 6 by means of a rivet 10 having an elongated head 11 which projects into a recess 11' formed in the adjacent strip 2. However, it will be noted that the head 11 does not project through the strip to detract from the neatness of appearance of the table, as is true in the case where rivets are employed. Also, it will be readily appreciated that spacing of the bracket from one of the adjacent strips 2, and insertion of the head 11 into the strip, serves to relieve considerable strain from the attaching screws 8, thus providing an extremely rigid and durable connection.

In order to provide for retention of the leg 3 in extended position, a brace 12 is pivotally connected to a plate 13, which, in turn, is secured to the inner face of the side strip 2. The brace 12 is preferably channelled throughout its length to add rigidity thereto and also straddle the head 14 of the stud 15 secured to the leg. The outer end of the brace is provided with tapered inturned flanges 16 which are normally engaged under the head 14 in the outer position of the leg,

as best shown in Figure 5, thus serving to prevent the brace from being disconnected from the stud until the leg is partially collapsed.

5 In order to latch the leg and brace against relative movement when the former is extended, the outer end of the brace is provided with an annular opening 17 adapted to receive the head 14, while the inturned flanges 10 engage the outer face of the leg. A depressed web 18, formed in the brace between its outer end and the opening 17, serves to engage the head 14 when the leg is swung to open position, thus forming a stop to prevent the stud from being withdrawn from the 15 channelled brace, whereupon the latter will then drop over the head 14 as heretofore explained. To insure proper engagement of the brace 12 and stud 15, the plate 13 is provided with a raised rib 19 that engages the 20 outer face of the brace when the latter is in extended position, thus exerting tension thereon to urge the brace against the head 14. When the leg is retracted, the same is torsionally retained by means of an additional rib 25 20, also formed in the plate 13 and adapted to frictionally engage the upper end of the brace.

In operation the leg is easily manipulated, 30 in that it is merely necessary to create a slight outward pressure on the brace 12 to release the head 14 from the opening 17, whereby the leg can be swung inwardly, and inasmuch as the head 14 is embraced by the sides of the 35 channelled brace 12, the latter will be collapsed simultaneously with the leg, and in closed position will nest between the outer face of the leg and the adjacent strip 2. In extending the leg it is merely necessary to 40 swing the same outwardly, whereupon the inward pressure created upon the brace by the rib 19 will cause the opening 17 to snap over the head 14 when the two are aligned.

From the foregoing explanation, taken in 45 connection with the accompanying drawing, it will be readily seen that an exceedingly simple, inexpensive and rigid means of attachment has been provided for pivotal connection of the table legs. At the same time 50 no screws or rivets are visible from the outside of the frame, and manipulation of the legs is materially facilitated, in that aside from releasing the brace from the stud carried by the leg, manipulation of latches and locking devices is entirely eliminated.

55 I claim:

1. In a folding table including a top, a leg pivotally carried by said top, a headed stud carried by the leg, and a channelled brace 60 pivotally carried by the top and embracing the head of said stud to latch the leg in extended position.
2. In a folding table including a top, a leg pivotally carried by said top, a headed stud 65 carried by the leg, and a channelled brace

pivots carried by the top and embracing the head of said stud to latch the leg in extended position, said brace being provided with an opening in its outer end for reception of the head of said stud.

70 3. In a folding table including a top, a leg pivotally carried by the top, a headed stud carried by the leg, and a channelled brace pivotally carried by the top and straddling the head of said stud, said brace being provided with an opening in its outer end for reception of the head of said stud and inwardly projecting flanges for engagement under said head.

75 4. In a folding table including a top, a leg pivotally carried by the top, a headed stud carried by the leg, a channelled brace pivotally carried by the top and straddling the head of said stud, said brace being provided with an opening in its outer end for reception 80 of the head of said stud and inwardly projecting flanges for engagement under said head, and means for creating lateral tension upon said brace to urge the same into engagement with said head.

85 5. In a folding table including a rectangular top, depending side rails carried by the top, a bracket formed from a single blank of material and secured to the inner faces of a pair of adjacent side rails, said bracket being spaced from one of the side rails and provided with spaced ears, a pintle carried by said ears and partially projecting into the spaced side rail, a leg pivotally mounted on said pintle, a headed stud carried by said leg, a channelled brace pivotally connected with the adjacent side rail and embracing the head of said stud, said brace being provided with an opening in its outer end for reception of the head of said stud, and means for creating lateral pressure on said brace to urge the same into engagement with said stud.

90 In testimony that I claim the foregoing I have hereunto set my hand at Milwaukee, in the county of Milwaukee and State of Wisconsin.

100 WILLIAM M. BOENNING.
